UNITED STATES PATENT OFFICE.

WILLIAM A. GRIMES, OF SPARTA, GEORGIA.

DESIGN FOR AN AX.

SPECIFICATION forming part of Design No. 25,154, dated February 11, 1896.

Application filed December 26, 1895. Serial No. 578,420. Term of patent 14 years.

To all whom it may concern:

Be it known that I, WILLIAM A. GRIMES, a citizen of the United States, residing at Sparta, in the county of Hancock and State of Georgia, have invented and produced a new and original Design for Ax-Heads; and I do hereby declare the following to be a full, clear, and exact description of the same, reference being had to the accompanying drawing, forming a part thereof.

The figure is a perspective view of my design.

The leading feature of my design consists in the eye 1, extending through the ax-head at an oblique to the general horizontal lines of the head, the raised portions 2 2, one on each side of the eye, also extending in the same direction as the eye. The length of the back or lower portion of the blade of the ax-head is less than the length of the front or upper portion, as indicated by the heavy lines in the drawing. Thus the general line of the

cutting-blade is pitched at an angle to the general line of the eye. As the degree of the angle of the eye with a perpendicular is 25 changed, so also should the degree of the angle of the blade with a perpendicular be varied, so that in the act of cutting the line of slant of the cutting-edge will be substantially parallel to the flat surface of an object 30 being cut.

The dotted lines in the drawing show how the head would be shaped if the back and front portions of the blade were the same length. 35

What I claim is—

The design for an ax-head substantially as set forth.

In testimony whereof I affix my signature in presence of two witnesses.

WILLIAM A. GRIMES.
